UNITED STATES PATENT OFFICE.

FRIEDERICH MÜLLER, OF HARTFORD, CONNECTICUT, ASSIGNOR TO THE WHITNEY MFG. CO., OF HARTFORD, CONNECTICUT, A CORPORATION OF CONNECTICUT.

METHOD FOR PRODUCING METALLIC BUSHINGS AND SIMILAR CYLINDRICAL BODIES, &c.

1,360,241.

Specification of Letters Patent. Patented Nov. 23, 1920.

Application filed December 31, 1914, Serial No. 879,912. Renewed August 3, 1920. Serial No. 401,081.

To all whom it may concern:

Be it known that I, FRIEDERICH MÜLLER, a citizen of the United States, residing at Hartford, in the county of Hartford and State of Connecticut, have invented certain new and useful Improvements in Methods for Producing Metallic Bushings and Similar Cylindrical Bodies, &c., of which the following is a specification.

10 My invention relates broadly and generally to new and useful improvements in methods for producing metallic bushings and similar cylindrical bodies.

An important object of the invention, 15 among others, is to produce a bushing which will be adapted for general use in the mechanical arts, but which will be particularly desirable for use in connection with power transmission chains, for instance, the well-known form of sprocket chains, and also of the link-belt type, which bushing may be made economically and rapidly from a blank of suitable metal, and which will have the advantages of being truly cylindrical both 20 exteriorly and interiorly, which will have the grain of the metal extended circumferentially thereof, strengthening the same against fracture under strain, and which will be of such form as to facilitate the assembling of the same in the completed chain 25 structure, particularly in connection with a machine for automatically applying said bushings to said chains, or the elements of chains.

30 A further object is to provide a method which will permit of the rapid, economical and efficient production of bushings having the advantages, above set forth.

The invention consists in the improvements to be more fully described herein-after, and the novelty of which will be particularly pointed out and distinctly claimed.

I have fully and clearly illustrated in the accompanying drawings to be taken as a 45 part of this specification, the improved bushing and a preferred embodiment of a machine for carrying out the method for producing said bushing.

In said drawings, Figure 1 is a top plan view of a preferred embodiment of the machine, certain parts being broken away to better disclose the operation and arrangement of certain parts thereof.

Fig. 2 is a vertical section on the line 2—2 of Fig. 1 looking in the direction of the arrows.

Fig. 3 is a section on the line 3—3 of Fig. 1.

Fig. 4 is a view in end elevation of a portion of the machine shown in Fig. 1, and 60 illustrating mechanism for operating a transfer slide.

Fig. 5 is a view in rear elevation and partly in section, of a portion of the machine showing the arrangement of the transfer 65 slide operated by the mechanism shown in Fig. 4, and also a slide for operating a mandrel.

Fig. 6 is a horizontal sectional view of a portion of the machine showing the location 70 of a slide member for subjecting a blank to a curling or forming die, certain parts being removed and the transfer slide shown in position to receive the stock when it is fed through the guide block and cut-off. 75

Fig. 7 is an enlarged sectional detail view of a stripping device.

Fig. 8 is a front view of the transfer slide showing the same in the position it assumes after removing the blank from the cutting 80 knife and presenting the same to the curling or forming die.

Fig. 9 is an enlarged detail view of the transfer slide.

Fig. 10 is an enlarged sectional view 85 through the transfer slide and showing the curling or forming die, and a sectional view of the mandrel located in said curling or forming die.

Fig. 11 is an enlarged vertical section 90 through the transfer slide block showing the cutting knife and its carrier, and the spring means for raising the same after the cutting operation.

Fig. 12 is an enlarged vertical sectional 95 view through roller means for forming and sizing the bushings.

Fig. 13 is an enlarged view in side elevation of the sizing block and showing a stock plate to guide flat stock as it is being pushed 100 into the curling or forming die.

Fig. 14 is a vertical sectional view of a modified form of the invention for feeding the stock in the form of previously cut blanks from the hopper to the curling or 105 forming die.

Fig. 15 is a sectional view on the line 15—15 of Fig. 14.

Fig. 16 is a sectional view showing another means for cutting off the stock from 5 a continuous strip and presenting it to the slide for moving it into the curling or forming die.

Fig. 17 is a section taken on the line 17—17 of Fig. 16 and showing the cutting-10 off plunger in lowermost position to serve as the guide for the stock as it is pushed into the curling or forming die.

Fig. 18 shows a plan and side elevation of 15 the blank of metal from which the bushing is made, and previous to being curled.

Fig. 19 is a view in end elevation of the blank previous to being curled and showing the rounded edges thereof.

Fig. 20 shows the position assumed by the 20 blank after being subjected to the action of the curling or forming die.

Fig. 21 shows the position assumed by the blank after being subjected to the forming 25 rollers.

Fig. 22 is an end view of the completed bushing after it has been passed through the curling or forming die, the forming rollers and the sizing bushing or die.

Fig. 23 is a longitudinal section through 30 the finished bushing.

I will first proceed to describe my invention in so far as it relates to the method and the article produced thereby, and will then describe one machine for carrying the 35 method into effect.

According to one way of carrying out my improved method I take a strip of metal stock of the desired nature and in which the fibers or grain extend lengthwise of the strip, and provide one or both, preferably both, edges thereof with rounded surfaces as indicated at *a* in Fig. 18 in the drawings, and from this strip cut a blank on a line extending transversely of the strip entirely across the same so as to produce a rectangular blank having two of its opposite parallel sides rounded, and the two other parallel sides cut at an incline to the plane of the blank as indicated at *b*. This blank is of such dimensions that its width from one rounded edge to the other will produce a bushing of corresponding length, and of such width from one inclined edge to the other that a bushing of the desired diameter and bore will be produced. I then take this blank and by a curling operation curl it on an axis extending parallel to the inclined or transverse sides, which produces a tubular body substantially similar to the body shown 50 in end elevation in Fig. 20 of the drawings. In this condition the inclined edges do not meet and a true cylinder is not produced. In performing this curling operation I prefer to wrap the metal blank about a mandrel or core located within a cylindrical die 60

member by forcing the blank with one of its inclined edges foremost into said die, and about the core by a movement at right angles to the longitudinal axis of the die and core, whereby the blank is by this engagement with the cylindrical surface of the die forced to curl or wrap about the core. A preferred form of this die and core will be described in detail hereinafter.

Upon completion of the curling operation 75 I subject said body so curled, and while still on the mandrel, to a compression operation whereby the meeting inclined edges are forced into engagement with each other and a true cylindrical contour is given to both 80 the bore and the circumference of said body. I accomplish this preferably by forcing said body, such as shown in Fig. 20, and while still on the mandrel, through a pair of compression die rollers which press and shape 85 said body to substantially the form shown in Fig. 21, in which the bushing is substantially cylindrical, but the cut edges of the blank are slightly spaced apart and parallel to each other. The body in the form shown 90 in Fig. 21, and while still on the core or mandrel, is then forced through a suitable compression die, which contracts the cylinder until it reaches the true cylindrical form shown in Fig. 22, in which the meeting 95 edges abut. In this condition the bushing is completed and is in condition for use in any situation desired. It will be noted that in producing this bushing the inclined cut edges in the completed article abut so as to 100 lie in a plane substantially radial to the longitudinal axis of the bushing. It will also be seen that in the completed article the fiber or grain of the metal extends about the bushing circumferentially which is of 105 great advantage in that this arrangement of the fibers provides a tough and more rigid bushing, which is not liable to be splintered under blows or strain, this being due to the fact that the bushing is not 110 brittle as the case would be where the grain runs longitudinally of the bushing. The rounded ends of the bushing are of advantage because it is not necessary to mill or reduce the same in order to insert the bushing 115 through openings in chain links, as the case would be where the bushings have squared ends, which are liable to have fins or spurs of metal interfering with the insertion of the bushing, and which must be 120 removed before assembling the bushing in a chain structure. The rounded ends will be found especially advantageous when used in a chain assembling machine, as the bushings can be readily fed to the chain and 125 assembled therein without regard to the form of the ends of the bushing. The action of the dies in compressing and forming the blank, results in the metal of the starting blank being drawn, stretched or 130

flowed so that the finished product is of greater length than the width of the starting blank and its circumference is greater than the length of the blank.

5 I will now proceed to describe my invention in so far as it relates to a machine for carrying out the method and producing the improved bushing above described. Referring to the drawings and particularly Figs. 10 1, 2 and 5 thereof:

1 designates a machine frame, the construction of which may be varied widely without affecting the scope of my invention, but preferably consisting of two wings or 15 sections 2, 3 arranged at right angles to each other, and a short wing or section 4 at right angles to the part 1 and extending in opposite directions from and in longitudinal alignment with the part 3. Mounted on 20 the upper portion of the frame between the parts 3 and 4 is a fixed block 5, bolted to the bed plate of the frame as at 6, and provided with a vertical opening 7 in which is arranged for vertical reciprocation, a knife 25 block or carrier 8, having a central vertical opening 9 in which is secured a chisel knife 10, the lower chisel end of which depends from said block 8 and co-operates with an anvil plate 12 secured in a recess 13 in the 30 bottom wall of the opening 7 in said block 5. The knife may be secured in the block 8 in any suitable manner as by a set screw 14 threaded through said block and engaging said knife with its inner end. This 35 knife has a double inclined chisel end, as indicated in Fig. 2 for a purpose to be presently set forth. The knife block or carrier 40 8 is normally urged upward by a pair of expansion springs 15, the ends of which respectively abut the bottom of the opening 7, on opposite sides of the plate 12, and the 45 lower portion of said block or carrier 8. By this means the carrier is automatically raised to locate the cutting edge of the 50 knife at a point above the plate 12. The knife carrier or block is held in place in the opening 7 by keeper plates 7^a, and is normally thrust laterally against said plates by means of a spring 8^a exerting its force 55 expansively against the back wall of said opening 7, and the vertical face of the knife carrier 8, the sidewise movement being at right angles to the line of cut, as will be clear from Fig. 2. The particular function 60 of this arrangement will be presently described. The plate or block 12 heretofore described is provided with a longitudinal passageway 16 leading to a point beneath the cutting edge of the knife, and opening 65 through the opposite side of the block 5 from that on which the knife reciprocates, and adapted to guide a strip of stock to the knife so that the latter may sever the necessary portion to form a blank for a bushing. 70 The strip of stock may be fed to the knife 75

in any suitable manner, but I prefer to employ the means shown to the left of Figs. 1, 2, 4 and 5. In this form of feeding means I provide upper and lower feed rollers, 17, 18 having bearings in pedestals 19, 70 mounted on the extension 4 of the machine frame. The upper of these rollers carries a gear 20 in mesh with a gear 21, mounted on a stub shaft 22 secured to one of the pedestals 19, said gear 21 having connected therewith a pawl and ratchet clutch mechanism 23, the operating lever 24 of which is reciprocated by a connecting rod 25 connecting said arm to a rock lever 26 fulcrumed on the frame as at 27, and having a 80 cam follower pin 28 engaging an eccentric cam groove 29 on a rotatable cam disk 30 mounted on a horizontally disposed power shaft 31. The power shaft is mounted in suitable bearings on the frame and may be 85 driven continuously in one direction by any suitable means. It will be apparent that the construction of the feeding means is such as to intermittently feed the strip of stock forward step by step to the knife. 90

Mounted on the frame, and in line with the part 2, and spaced from the block 5 and the knife 10 is a transversely arranged block, hereinafter referred to as a die block 32 having a vertical stop face 33 against which 95 the inner end of the strip of stock abuts previous to being cut off by the knife, so that the strips cut will always be of a determined length, the length of blank cut corresponding to the distance from the knife edge 100 to said face 33. This length may be regulated by providing said stop face with removable plates 34 of different thicknesses, adapted to be secured to the die block by bolts 35, whereby the said stop face can be 105 located at different distances from the line of cut. It will also be understood that the feeding connections may be adjusted to regulate the amount of strip fed to the knife to correspond to the distance from the line 110 of cut to said cut-off.

Arranged to reciprocate across the outer face of the knife 10, and between the block 5, and the block 32, is a reciprocable transfer slide 37 having a dovetail sliding connection 36 with a dovetail groove in the vertical face of the block 5. This transfer slide in retracted position extends by the knife and the opening 16, and is provided with a slot 38 to receive the end of the strip being severed, and transfer the same to a forming die to be presently described. This transfer slide in its retracted position, is arranged with said slot in line with the line of feed of the strip of stock, so as to receive that end portion of the strip which is to be severed and which abuts the face plate 34. The transfer slide is timed to transfer the severed portion of the strip, which is to be formed into the bushing, to a point to one 120 125 130

side of the knife and so as to bring its slot 38 in line with a forming or curling slide 39 which reciprocates at right angles to the path of movement of the transfer slide 37 5 and moves the metal blank to the curling or forming die. The transfer slide is also formed with a vertical slot 40 opening through the bottom edge of the slide into said slot 38, for a purpose to be presently set forth. The curling or forming slide consists of a bed portion 41 sliding in guideways 42 in the main frame from which rises a vertical blade member 43, the upper edge portion of which is adapted to reciprocate 10 through the vertical slot 40 formed in the transfer slide and to project up far enough to engage the metal blank in the slot 38 to dislodge said blank from said transfer slide, substantially as shown in Figs. 6, 8 and 10 15 of the drawings.

I will now describe the curling or forming die into which the metal blank is forced by the curling or forming slide 39, to be curled to the form shown in Fig. 20 of the drawings. For this purpose the die block 32 is formed with a horizontal cylindrical bore 44 extending at right angles to the line of reciprocation of the curling or forming slide, and at an intermediate point of this 25 bore is located a cylindrical die bushing 45 held by guide bushings 46, 47, arranged in said cylindrical bore on opposite sides of the cylindrical die, the bushings 46 being held in position by set screws 48 threaded through 30 the upper portion of said block 32. This cylindrical die bushing 45 is open at one edge through a slot 49 substantially tangential to the circumference of the internal cylindrical wall of the die, as clearly shown in 35 Fig. 10 of the drawings. The arrangement of the die and curling slide is such that when the metal blank is dislodged from the transfer slide and pushed forward by the curling slide, said blank will be pushed 40 through the slot or opening 49 by the curling slide and curled up against the inner cylindrical surface of the curling die, the blade 43 of the curling slide entering the said slot 49, so that the entire metal blank 45 is passed into the cylindrical bore of the curling die 45. The die block 32 may be recessed adjacent the entrance to the die, as 50 32^a, to receive a guide member 32^b bolted to the die block and having horizontal parallel 55 spaced arms 32^c upon which the blank slides from the transfer slide to the die when moved by the curling slide blade 43, said blade 43 moving between said arms.

Arranged to slide in the said bore 44 60 through the die block 32, is a combined pusher and mandrel or core 50 carried by a reciprocating bed 51, sliding in guideways 52, on the frame part 3, said mandrel or core being adapted to reciprocate through the

sleeve 47 heretofore described, closely fitting 65 the bore of the same, and having at its end a reduced cylindrical core part 53 which, when the mandrel is in one position is located centrally of the cylindrical curling die 45, so that said core part 53 forms a mandrel 70 or core about which the metal blank is curled in the space between the part 53 and the inner wall of the curling-die 45 when said blank is forced into the curling die 45 by the curling slide 39. At the base of the 75 core part 53 is a shoulder 53^a which serves a purpose to be presently described.

It will be understood that the feeding mechanism, the knife, the transfer slide, curling slide, and the mandrel are so timed so in their movements that the strip will be presented to the knife; then severed by the knife, whereupon it will be moved by the transfer slide into the path of movement of the curling slide and the curling slide will 85 then force it into the curling die 45 around the core portion 53 of the mandrel, the mandrel-moving means having a dwell for a period sufficient to hold the core-piece 53 in the die 45 during the curling of the blank, 90 and the transfer slide having a dwell long enough for the curling slide to pass through the same in forcing the blank to the die and then return to initial position. Any suitable means may be provided for producing 95 the sequence of movements just set forth which means may be varied without departing from the spirit and scope of my invention.

I will now proceed to describe one way 100 of operating the knife to cut the strip. Mounted on the part 3 of the frame is a standard comprising vertical spaced arms 54 upon which is fulcrumed a rock lever 55 adapted to engage the upper portion of the 105 chisel knife to move the same downward to engage the strip to cut off a bushing blank. I preferably provide an adjustable engagement between one end of said lever and the knife, the same comprising a thrust bolt 56 110 threaded through the lever and adapted to engage with its lower end upon the upper end of the knife, so that when the said lever is rocked in one direction, the knife will be moved down to sever the strip, and when the 115 lever is moved in the opposite direction, the springs 15 will act on the carrier block to raise the knife. The forward end of the lever is also provided with a stop screw 57 threaded therethrough and adapted to engage the 120 upper surface of the block 5 to limit downward movement of the lever so that the knife in its downward movement will just meet the block 12, and not cut into the same or be dulled thereby. The lever may be timed 125 by any suitable means so as to descend subsequent to the feeding of the strip, and for this purpose a reciprocating plunger 58 slid-

ing in a vertical guide 59 on the main frame and operated by an eccentric cam 60 on the shaft 31 may be employed.

The transfer slide 37, may be reciprocated 5 by a lever 61 carried by a horizontal rock shaft 62, and having its free end in engagement with a pin 63, connected to the said slide and projecting laterally therefrom through a slot 64 in the block 5. The shaft 10 62 is rocked by an arm 65 connected thereto and engaging a cam groove 66 in the cam disk 30 heretofore described.

The curling slide may be operated by a grooved cam 67 mounted on the shaft 31, 15 and engaging a pin 68 carried by the base piece of said curling slide, and the mandrel may be operated by a bell-crank lever 69, fulcrumed on the frame as at 70, and having one of its arms 71 pivotally engaging the 20 mandrel carrier or bed 51 as at 72, and its other arm 73 provided with a pin 74 engaging a grooved cam 75 also mounted upon the shaft 31 to rotate therewith. So far the time relation of the parts described, is 25 as follows: The feeding mechanism feeds the strip forward a distance sufficient to supply one bushing blank, whereupon the knife 10 descends, severing the blank from the strip, then the transfer slide 37 moves 30 the severed blank away from the knife into the path of movement of the curling slide 43, and the latter then moves forward to engage the blank and force the same into the curling die 45, and around the core-piece 35 53 of the mandrel 50.

The lateral sliding movement of the knife carrier, in the form shown in Fig. 2, is provided so that when the knife descends it may have sufficient lateral play to produce the 40 inclined edge on the rear of the blank cut-off, and also on the forward edge of the strip of stock. The lateral movement also permits the carrier and knife to move back from the cut blank so as not to jam or bend 45 the same against the stop face on the block 32, due to the chisel knife forcing the strip of stock and the cut blank away from each other.

These parts then return to their natural 50 positions for the cutting and transfer of the metal blank, during which period the mandrel 50 with the core-piece 53 moves forward with the curled metal blank and forcing the latter through a pair of upper and lower 55 compressing and forming die rollers 76, arranged in the bore 44 whereby the metal blank in the form shown in Fig. 20 is reduced to the form shown in Fig. 21, and the mandrel 50 continues its movement carrying the blank in the form shown in Fig. 21 60 into a tapered die bushing 77 in longitudinal alinement with the die 45, whereby the bushing blank is compressed and shaped to the form shown in Fig. 22, which is the completed commercial article. In the forward 65

movement of the mandrel, the shoulder 53^a engages one end of the bushing curled on the fore-part 53, so that the proper force is given the bushing to carry it through the rollers 76 and the die 77. After being subjected to the action of the tapered die bushing 77, the bushing is carried on still farther by the mandrel until it reaches a stripping chuck 78 having spring hook arms 79 which catch over the rear end of the completed bushing and holds the latter so that when the mandrel 50 is retracted to its initial position, as shown in Figs. 1, 3 and 6, the completed bushing is stripped from the core portion 53 of the mandrel. As soon as the mandrel is returned to its initial position, the feeding mechanism, knife, a transfer slide and curling slide, repeat the operation heretofore described to again curl the blank about the core portion of the mandrel, and the latter then forces the curled blank successively through the compressing or forming rollers, and the tapered die to the stripping chuck.

In the forms of the invention shown in 90 Figs. 14 and 15, the cutting mechanism and the transfer slide, and its operating mechanism may be omitted, because the blanks from which the bushings are to be made, are previously cut by other means. In this 95 form of the invention I provide a hopper arranged over the pair of separated supports or arms 32^c spaced from the bottom of said hopper, substantially the thickness of the blank, and adapted to support a stack 100 79^a of previously cut blanks arranged one above the other in the hopper; and adapted to gravitate one by one onto said support in the path of movement of the curling slide. In this arrangement, the curling slide 39 105 reciprocates between the spaced supporting members or arms 32^c, and removes one blank at a time from the bottom of the supply stack in the hopper and forces the blank into the curling die for the purpose heretofore 110 described.

In Figs. 16 and 17, as shown, a further embodiment of the invention in which the transfer slide is dispensed with, and the cutting member transfers the cut blank from 115 a strip into position to be engaged by the curling slide to be presented to the curling die. In this form, a cutting plunger 80 is arranged in the block 32 to reciprocate by, and shear against, the vertical squared end 120 of that portion of the block 5 through which the strip of stock is fed, said cutting block being urged to retracted position by a spring 81 and moved to shear the metal by the same means shown in Figs. 1, 2, 3 and 5. In its 125 downward movement, the cutting blank moves the cut metal blank down into the upper surface of spaced guide members 32^c, from which point it is moved by the curling slide into the curling die in the same man- 130

ner as heretofore described. The machine above described is adapted for manufacturing bushings of various sizes within limits, by merely interchanging the die bushings 5 so as to provide one of the diameter to produce a bushing of the desired size, and by the interchange of mandrels with core-pieces corresponding to the bore of the bushing.

10. It will be understood that, in small bushings wherein the metal stock is necessarily thin, it will not be obligatory to provide the inclined edges on the blank before curling. In this case the shearing means shown 15 in Figs. 16 and 17 may be employed.

What I claim and desire to secure by Letters Patent of the United States is:—

1. The method of forming metallic bushings, which consists in forming a rectangular metal blank and with the fiber or grain 20 of the metal extending parallel to opposite sides, and shaping said blank to cylindrical bushing form with the fiber extending circumferentially of the bushing.

25. 2. The method of forming metallic bushings, which consists in taking a strip of metal and cutting said strip entirely across the same to produce a blank having inclined edges and shaping said blank to cylindrical form with said inclined edges facing inwardly and meeting lengthwise of the bushing.

3. The method of forming metallic bushings, which consists in taking a strip of 35 metal and cutting entirely across the same to produce a blank having inclined edges at right angles to said rounded edge and subsequently shaping said blank to cylindrical form with said inclined edges facing inwardly and meeting lengthwise of the bushing.

4. The method of forming metallic bushings, which consists in forming a flat right angle blank having inclined parallel edges 45 on two of its sides, curling said blank to form a substantially cylindrical body with said inclined edges adjacent each other and facing inwardly, and subsequently compressing said body to cylindrical form with said 50 adjacent edges in engagement with each other along the line extending lengthwise of the bushing.

5. The method of forming metallic bushings which consists in forming a flat right-angle blank with the fiber or grain of the metal extending parallel to two opposite edges, curling said blank on an axis at right-angles to said two opposite edges to form a substantially cylindrical body with the 55 fiber or grain of the metal extending circumferentially of the cylinder, and subsequently compressing said body to cylindrical form with said adjacent edges in engagement with each other along the line extending 60 lengthwise of the bushing.

6. The method of forming metallic bushings which consists in forming a flat right angle blank having opposite parallel edges on two of its sides and parallel edges on its other two sides, and with the fiber of the 70 metal extending parallel to said first-named edges, curling said blank on an axis at right angles to said first-named parallel edges to form a substantially cylindrical body, and subsequently compressing said body by a suitable 75 operation and then elongating the same parallel with its axis by drawing or flowing the metal so that the finished product is of greater length than the width of the starting blank.

7. The method of forming metallic bushings which consists in taking a flat right angle blank having the fiber or grain of the metal extending parallel to one side edge of the blank, curling said blank on an axis 85 at right angles to said edge to form a substantially cylindrical body wherein the fibers extend circumferentially of said body, compressing said body by suitable rollers and thereby bringing the edges of the blank into 90 engagement, and then elongating the said body by forcing the same through a suitable die.

8. The method of forming metallic bushings which consists in taking a flat right angle blank having the fiber or grain of the metal extending parallel to one side edge of the blank, curling said blank on an axis at right angles to said edge to form a substantially cylindrical body wherein the fibers 100 extend circumferentially of said body, compressing said body by suitable rollers and thereby bringing the edges of the blank into engagement, and then elongating the said body by forcing the same through a tapered 105 die.

9. The method of forming metallic bushings which consists in taking a blank having opposite parallel edges wherein the fiber or grain of the metal extends parallel to one 110 side of said edges, curling said blank on a mandrel to form a body of substantially cylindrical form, but in which the edges do not meet, passing said body while still on the mandrel through suitable die rollers to 115 make the body more nearly cylindrical, and moving the meeting edges closer to each other, and then elongating the said body and causing said edges to abut against each other and thereby complete the desired cylindrical 120 form by forcing the same through a suitable die.

In testimony whereof I have hereunto signed my name in the presence of two subscribing witnesses.

125

FRIEDERICH MÜLLER.
